LADY'S HANDBAG OR SIMILAR ARTICLE

Gustav G. Rona, New York, N. Y.

Application June 24, 1949, Serial No. 3,518

Term of patent 3½ years

(Cl. D87—3)

To all whom it may concern:

Be it known that I, Gustav G. Rona, a citizen of the United States, residing at New York city, in the county and State of New York, have invented a new, original, and ornamental Design for a Lady's Handbag or Similar Article, of which the following is a specification, reference being had to the accompanying drawing, forming a part thereof.

Fig. 1 is a perspective view of a Lady's handbag or similar article, showing my new design.

Fig. 2 is a similar perspective view illustrating the flap element in an open position.

Fig. 3 is a perspective view on a smaller scale showing the opposite side and end from those shown in Figs. 1 and 2, and illustrating the handbag in an open position.

I claim:

The ornamental design for a lady's handbag or similar article, substantially as shown.

GUSTAV G. RONA.
